UNITED STATES PATENT OFFICE.

ELIHU THOMSON, OF SWAMPSCOTT, MASSACHUSETTS, ASSIGNOR TO THE GENERAL ELECTRIC COMPANY, OF NEW YORK.

ELECTRIC-ARC LAMP.

SPECIFICATION forming part of Letters Patent No. 678,916, dated July 23, 1901.

Application filed December 26, 1899. Serial No. 741,540. (No model.)

To all whom it may concern:

Be it known that I, ELIHU THOMSON, a citizen of the United States, residing at Swampscott, county of Essex, State of Massachusetts, have invented certain new and useful Improvements in Electric-Arc Lamps, (Case No. 1,090,) of which the following is a specification.

The present invention relates to electric-arc lamps, and has for its object to improve their construction and operation.

In the accompanying drawings, which illustrate an embodiment of my invention, Figure 1 is a sectional view of an arc-lamp. Fig. 2 is a diagram of connections. Fig. 3 is a sectional view of the guide for the carbon-containing tube, taken on the line 3 3 of Fig. 1. Figs. 4 and 5 are detail views of the upper-carbon holder. Figs. 6 and 7 are enlarged views of the means employed to compensate for fluctuations in the line-current, and Figs. 8 and 9 are detail views of a modified form of carbon-holder.

The lamp-frame is composed of two vertical rods A, which are seated in the casting A' at their upper end and are connected by the yoke A² at their lower ends. Mounted in the yoke is a suitable holder A³ for the arc-inclosing globe B and the lower carbon C. Resting on the top of the inclosing globe is a gas-cap D, which may be of any suitable construction. The cap is provided with a central opening, and passing through this opening is the upper carbon or electrode C'. Surrounding the upper carbon is a tube E, and on the lower end of the tube is a clutch F, the jaws of which are arranged to grasp the upper carbon and regulate the feeding thereof. To the upper end of the tube is secured a dash-pot piston G, which works within the cylinder G'. This dash-pot is intended to check sudden movements of the upper carbon. Surrounding the carbon-containing tube E is a tubular iron core or armature H, the upper extremity of which is tapered, so that the actuating-magnet will exert a substantially even pull over a wide range of movement. For the purpose of guiding the tube E in its vertical movements small rollers I are employed. These rollers are mounted in supports located above and below the

actuating-magnet, the upper rollers being mounted in a tubular piece I', having slots for receiving the rollers, and a bottom flange which rests on the top of the spool of the magnet and is secured thereto, while the bottom rollers are carried by a plate I², which is secured to the projections I³, extending downward from the magnet-spool. The rollers are of the shape shown in Fig. 3 and are located in such a manner that the tube is permitted to move vertically with perfect freedom, but is prevented from twisting out of line from any cause. In order to prevent undue friction between the parts, the piston G of the dash-pot is so connected to the tube E that a certain amount of lateral movement is permitted. If desired, however, the connection between the dash-pot piston and tube may be a rigid one and the cylinder G' permitted to move slightly in its support.

It is well known that after differential lamps have been in operation for a time more or less great certain changes in the "pick-up" and "feeding" voltages occur. This is caused by the changes in resistance of the magnet-coils, whereby the proper relation or balance between them is more or less destroyed. Various attempts have been made heretofore to overcome this objection with more or less success. In accordance with my invention the difficulties above referred to are overcome by providing an additional winding made of some metal having a low temperature coefficient—as German silver, for example—which is connected around the series winding and works in opposition thereto, at the same time assisting the shunt-coil. Now as the resistance of the shunt and series coils increases more current will flow through the third winding and by proper adjustment as to length and cross-section may be made to compensate exactly for the decrease in effect of the shunt-coil, or it may be arranged to effect any other desired relation between the windings.

Referring to the drawings, J represents the compensating winding and is shown as being wound on a suitable spool, having a damping-tube K for decreasing the fluctuations in magnetism. Surrounding the compensating winding is the usual series winding L, and

outside of that is the usual shunt-winding M. The arrangement of these windings may be changed—that it to say, the compensating winding may be placed between the other 5 two or on the outside, as desired. The upper and lower flanges of the magnet-spool are made of iron and form a part of the magnetic circuit. They are preferably connected magnetically outside of the windings. The connections of these windings are best shown in 10 Fig. 2. The series coil L is in series with the carbons and the arc, the shunt-coil M is connected across the terminals of the lamp, and the compensating coil J is connected at one 15 end to the top of the series coil and at the other end to the bottom. The turns of the series winding are opposed to the turns of both the shunt and the compensating winding. The compensating winding being in 20 shunt to a number of the series turns or to the entire series coil, more current will pass through the compensating winding after the series coil is heated, and the virtual effect thereof is to weaken the power of the series 25 coil and in this way to compensate either wholly or in part for the weakened effect of a shunt-circuit winding as the lamp heats. The proportions between the various windings will vary considerably with the weight 30 of the parts to be lifted and other details of construction, so that no set rule can be given as to the relation between the ampere-turns of the various windings. This much can be said, however, that the change in the lifting 35 effect of the series coil should be as nearly as possible equal to the change in effect of a shunt-winding due to heating. A skilled constructor will have no difficulty in adjusting the lamp for practical useful results.

40 In so-called "constant-current" arc-light circuits, it sometimes happens that the current strength varies slightly from time to time. The ordinary differential winding or arrangement of the lamp parts will to a certain extent compensate for these changes, but not entirely so. I propose to carry this compensation one step farther and to provide a regulator in addition to the ordinary lamp mechanism which will automatically maintain the current substantially constant in the regulating-coils irrespective of changes in current strength. In carrying out this feature of my invention a shunt resistance is provided, which is connected around the series 45 coil in such a manner that as the current in the line-circuit increases more or less of the current is shunted past the coil, but when the current decreases for any cause to a point below normal the effect of the shunt is decreased.

50 Referring to the drawings, N represents a magnet the winding of which is connected in series with the series coil L. The connection of the magnet is best shown in Fig. 6, 55 wherein N' represents a frame-piece forming a support for a fixed electrode O. Pivotal

70 supported by the frame-piece, but insulated therefrom, is an arm N², in which is mounted an electrode O'. It is preferable to give the meeting faces of the electrodes a slight convexity, so that the extent of contact will be small. It is desirable, although not necessary, that a spring N³ be employed to hold the electrodes in contact. The parts are preferably so constructed and arranged as to permit a moderate percentage of the main current 75 to be shunted past the series coil L at all times. When the current in the circuit increases, the magnet N attracts its armature with an increased force, thereby making better contact between the electrodes O and O', and more current is shunted around the series coil L. On the other hand, when the amount of current in the circuit decreases the contact 80 between the electrodes becomes poorer, and less current is shunted around the series coil. By this arrangement it is possible to relieve 85 in a measure the disturbance which will occur in the length of the arc when the main-line current fluctuates, and by carefully proportioning and adjusting the parts variations 90 in current strength of from twenty-five to thirty per cent. may be compensated for.

95 The carbon-holder for the upper carbon is best shown in Figs. 4 and 5, wherein P represents a split metal sleeve which is arranged to hold the upper carbon C'. Formed integral with or otherwise secured to the top of the sleeve is a rod P', having a cap P² secured to its upper end, and loosely mounted thereon 100 is a number of beveled disks or cones P¹. The top of the sleeve is beveled in a manner similar to the disks, and located between the disks is a number of small balls P³. As shown, a single row of balls is provided between the upper end of the sleeve and the first disk P¹, while between this disk and the second are two rows of balls and between the upper disk and the cap three rows of balls 105 are shown. The disks P¹ being provided with beveled or slanting surfaces on the top and bottom each disk furnishes bearing-surfaces for two rows of balls. The balls are mounted between the disks in such a manner that they 110 are free to move and are made of some good conducting metal—as copper, for example. It is preferable to heavily plate them with silver. It is also desirable to silver-plate the surfaces on which the balls travel, and I have found it desirable, although not necessary, to silver-plate the inside of the carbon-containing tube E. I do not consider the cones or disks essential elements of my invention, for they may be dispensed with and the space between the cap and the sleeve 115 filled with balls; but they are useful in securing more perfect conductivity and in giving the balls regular positions, with a tendency to move outward into engagement with the carbon-tube. The holder just described 120 possesses many features of advantage, as it 125 is simple to construct, insures many points

of contact between the tube and the carbon, and offers little opposition to the movements of the holder when the lamp is in operation.

In Figs. 8 and 9 a carbon-holder is shown having means for retaining the balls in place. This arrangement is desirable where it is necessary or desirable to remove the holder from time to time. The holder consists of a split sleeve, as before, and mounted on the rod P' 10 is a number of sheet-metal disks P⁴, each having beveled or slanting surfaces and fingers or projections P⁵, which extend between the balls for retaining them in place. Between the cap P² and the upper disk P⁴ is a coiled 15 spring P⁶, which tends at all times to force the disks together, thus moving the balls into engagement with the carbon-tube.

The lamp is provided with a mechanical cut-out Q and a magnetic cut-out R, both of 20 which are of ordinary construction and work in the usual manner.

What I claim as new, and desire to secure by Letters Patent of the United States, is—

1. In an electric-arc lamp, the combination 25 of a movable tubular armature, shunt and series windings surrounding the armature, and a compensating winding also surrounding the armature, the coefficient of which differs from either the shunt or the series 30 winding.

2. In an electric-arc lamp, the combination of upper and lower carbon electrodes, a shunt-winding, a series winding, and a compensating winding, which windings are concentrically disposed one over the other and surround the upper carbon; the compensating winding being arranged to form a shunt to the whole or a portion of the series winding, the last-mentioned windings having different 35 coefficients.

3. In an electric-arc lamp, the combination of a carbon-tube, an armature surrounding the tube, a magnet-spool surrounding the tube and armature, a compensating winding 45 mounted thereon, a series winding wound concentrically with respect to the first and connected in parallel relation thereto, and a third or compensating winding wound concentrically with respect to the other windings 50 and acting on the armature and having a resistance and coefficient which differ from either of the windings.

4. In a constant-current-arc lamp, the combination of magnetic means for separating 55 and feeding the carbons, a resistance path or circuit and means controlled by the current flowing in the main-line circuit for shunting a part of the main-line current through the resistance path or circuit and past the said 60 magnetic means when the current on the line rises and for decreasing the amount of the current so shunted when the main-line current falls below a certain point.

5. In an electric-arc lamp for constant-current circuits, the combination of a series coil 65 for drawing the arc, a more or less imperfect shunt around the coil, and a magnetic means

included in circuit with the series coil for varying this shunt in accordance with changes of current in the main-line circuit.

6. In an electric-arc lamp, the combination 70 of an armature which controls the feeding of an electrode, a coil which acts directly on the armature and is subjected to changes in current strength, a second coil which is in series with the first and is always in active service when the lamp is in operation, and automatic means controlled by the second coil for maintaining the current constant in the first-mentioned coil.

7. In an arc-lamp, the combination of differential windings, a regulating-magnet in series with one of the windings, and means controlled by the magnet for shunting more or less of the current around the winding 85 which is connected in series with the regulating-magnet.

8. In an electric-arc lamp, the combination 90 of a series-wound actuating-coil, a more or less imperfect shunt for the coil comprising two pieces of carbon, an arm for moving one piece of carbon with respect to the other, and a magnet included in the main circuit for moving the arm.

9. In a constant-current arc-lamp, the combination 95 of an actuating-coil in series with the arc, a more or less imperfect shunt around the coil, comprising carbon points, a spring for holding the points in contact, and a magnet included in the main circuit for assisting the spring in accordance with the current flowing in the arc-circuit.

10. In a carbon-holder and contact device, the combination of a split sleeve, a rod secured thereto, beveled disks loosely mounted 105 thereon and arranged in pairs with the beveled faces oppositely disposed, and rows of balls located between the disks and supported thereby.

11. In a carbon-holder and contact device, 110 the combination of means for holding the carbon, two or more beveled disks having projections or fingers formed integral therewith, and a row of balls located between the beveled disks and retained in place by the 115 projections.

12. In an electric-arc lamp, the combination 120 of a carbon-containing tube, a dash-pot, a support for one element of the dash-pot which is secured to the magnet, a second element 125 being secured to, and movable with the carbon-containing tube, the two elements being capable of adjustment with respect to each other, roller-guides mounted in the support and engaging with the upper end of the tube, and roller-guides mounted in a second and 130 stationary support for engaging the lower end of the tube.

13. In an electric-arc lamp, the combination 130 of a magnet having iron spool-flanges, extensions on one of the flanges, a ring mounted on the flange, and roller-guides which are carried by the ring.

14. In a differential arc-lamp, the combina-

tion of a series winding, a shunt-winding, and a compensating winding which is active when the lamp is in operation and is permanently connected in shunt around the series winding and wound on the same spool with the shunt-winding.

15. In a differential arc-lamp, the combination of a series winding, a shunt-winding, a feeding mechanism acted upon differentially by both of the windings, a compensating winding connected in shunt around the series

winding and wound on the same core as the shunt-winding, the shunt-winding and the compensating winding being wound in the same direction and therefore acting to assist each other.

In witness whereof I have hereunto set my hand this 22d day of December, 1899.

ELIHU THOMSON.
